(57) **CLAIM**

The ornamental design for a tripod head, as shown and described.

DESCRIPTION

FIG. 1 is a perspective view of a tripod head showing my new design.

FIG. 2 is a reduced right side elevational view of the tripod head of FIG. 1.

FIG. 3 is a reduced front elevational view of the tripod head of FIG. 1.

FIG. 4 is a reduced left side elevational view of the tripod head of FIG. 1.

FIG. 5 is a reduced rear elevational view of the tripod head of FIG. 1.

FIG. 6 is a top plan view of the tripod head of FIG. 1.

FIG. 7 is a bottom plan view of the tripod head of FIG. 1.

FIG. 8 is an enlarged front elevational view of the tripod head of FIG. 3; and,

FIG. 9 is an enlarged right side elevational view of the tripod head of FIG. 1, showing the camera platform and tilt handle tilted 90 degrees.

The broken line showing of a camera in FIG. 8 is included for the purpose of illustrating use and environment and forms no part of the claimed design.
